BEADING OR FLARING MACHINE WHICH VARIES OFF-CENTER POSITION OF TOOL

Henry E. Hull and Emmett C. Hartley, Cleveland, Ohio, assignors to The Parker Appliance Company, Cleveland, Ohio, a corporation of Ohio

Application September 18, 1943, Serial No. 502,984

18 Claims. (Cl. 153—79)

1

This invention is a machine for beading and flaring portions of tubular articles.

One of the objects of the invention is to provide a mechanism of simple construction, which is capable of use for operating a beading tool or a flaring tool, as desired. A further object is to provide a machine of the type described having a tool-carrying block of novel construction so constructed and arranged that it may be quickly and accurately adjusted to off-center position with respect to the work. A further object is to provide a simple means for adjustably varying the extent of said off-center adjustment.

The invention will be hereinafter fully set forth and particularly pointed out in the claims.

In the accompanying drawings:

Figure 1 is a side elevation of the machine constructed in accordance with the invention, parts being shown in section.

Figure 2 is an end view.

Figure 3 is a top plan view, with the driving motor removed.

Figure 4 is a detail sectional view on the line 4—4, Figure 1.

Figure 5 is a detail sectional view on the line 5—5, Figure 1.

Figure 6 is a detail sectional view illustrating a flaring die and flaring cone in place of the beading die and roller of the preceding figures.

Figure 7 is a side view of a modified form of the invention.

Figure 8 is a longitudinal sectional view of Figure 7.

Figure 9 is an end view of the modification illustrated by Figure 7.

Figure 10 is a cross-section on the line 10—10, Figure 7.

Referring to the drawings, 10 designates a housing of any desired construction. Located within the housing is a spindle 11, which is rotatively mounted in suitable anti-friction bearings 12, and operatively connected with the shaft 13 of a motor M, through suitable gearing G. The bearings 12 are maintained in separated relation by a sleeve 14.

The spindle 11 is provided with an axial bore 15 of rectangular cross section, and slidingly mounted for axial movement therein are cam blocks 16, each having a plurality of inclined cam faces 16a. Said cam blocks are of a cross section corresponding to that of the bore 15, so that they will rotate with the spindle, and extend the full width of the bore 15. Slidably mounted between the cam blocks 16 is the tool-carrier block 17 of rectangular cross section, having cam faces

2

17a complementary to the cam faces 16a of the cam block. The sides of block 17 engage the sides of the bore 15, so that the block 17 will also rotate with the spindle 11. The block 17 is also provided with a transverse, axially elongated slot 19, having an offset portion 19a to form a transverse opening approximately L-shape in cross section. A pin 20, which is anchored to the spindle, extends through the slot 19. The outer end of the housing is closed by a cover plate 21.

The cam blocks 16 are connected in suitable manner to an interposed operating block 25, as by screws 26, so that said operating block 25 and the cam members may be moved in unison.

15 The operating block 25 is provided with a reduced portion 27 separated by annular shoulders 28. It is also provided with an axial bore 29, which is internally screw threaded to adjustably receive the threaded stem 30 of a stop member S. Said 20 stop member extends through said bore to a position adjacent the inner end of the tool block 17, and is held in any adjusted position by a lock nut 31.

25 Rotatively mounted in a yoke 32 of the housing 10 is a lever L on which is mounted a supplemental yoke 33, held against rotation by means of a key 34 and a set screw 35. Mounted in the arms of the supplemental yoke 33 are studs 36, which extend toward each other into the space 30 between the shoulders 28 of the operating block 25, and are provided with rollers 37 to engage said flanges. By means of this arrangement, it will be observed that sliding reciprocative movements may be imparted to the cam blocks by 35 rocking the lever 33 in either direction, movement being imparted to the cam blocks by the action of the rollers 37 against the respective shoulders 28.

The bore 18 of the block 17 is internally 40 threaded to receive an adjustable externally threaded adjusting sleeve 40, which is held in adjusted position by means of a lock nut 41. A spring pressed detent 42 releasably engages a groove in the tube-working-tool spindle 43. Suitable bearings 44 are provided in the sleeve 40 to permit rotation of the block 17 and said sleeve with respect to the tool T.

50 Any suitable means may be employed for supporting the tube W in proper position with respect to the tool. For purposes of illustration, a desirable type of mechanism is shown in the drawings. Referring more particularly to Figures 2 and 3, 50 designates a fixed jaw which is attached to the housing 10 in suitable manner, such as by means of bolts 51. Pivotally mounted

on the fixed jaw 50, at 52, is a movable jaw 53. An actuating lever 54 is pivotally mounted to the fixed jaw at 55, and is connected to the movable jaw 53 by a link 56, said link being pivotally connected to the lever and the movable jaw, respectively. Each jaw is provided with a die receiving recess 57, which is provided with a stop shoulder 58. Each half of a sectional die block 59 is held in position in the jaw by means of a dog 60, having a pin 61 complementary to a recess in the adjacent die block section. The dog 60 is mounted on a spring pressed member 62, the spring 63 of which urges it in a direction to maintain the pin 61 in engagement with its recess. See Figure 6. When it is desired to remove the die from the jaw, the member 62 is pressed inwardly against the tension of its spring 63, so as to disengage the pin 61 from the die. Said member 62 is then rotated so that the dog clears the die. Each die is also preferably provided with a recess 66, to receive two rubber slugs 67, which are held in place by a plate 68 attached to the die members by screws 69. Each slug is of sufficient thickness and width to extend a slight distance axially beyond the end of its recess 66 so as to provide a clearance space to permit adjustable compression upon the block by the plate 68, by adjustment of the screws 69. In practice, the clamping jaws are opened by moving the lever 54 to the dotted line position of Figure 2 and are brought into clamping relation with the work W by movement of the lever to the full line position.

The sectional dies are preferably constructed so that the work W is clamped solely by the rubber slugs 67. In this manner, the flat surfaces of the dies engage one another to form a perfect die into which the work is expanded during beading or flaring, regardless of slight variations in the outside diameter of the work.

In operation, the lever L is moved to the extreme left dotted-line position—Figure 1—which causes the cam blocks 16 and the tool-carrier block 17 to move to the left to clear the work. While the lever and the tool-carrier block are thus positioned, the work may be disengaged from the clamping jaws. The lever L is then moved to the full-line position, indicated in Figure 1. During this movement the cam blocks 16 and the tool-carrier block 17 travel together in an axial direction, because pin 20 in slot 19 will prevent any off-center movement of the block 17. Therefore, the cam surfaces 16a and 17a will interlock to prevent relative sliding movement. Relative axial movement of the tool-carrier block 17 to the right, as viewed in Figure 1, is arrested when the pin 20 abuts against the end wall of slot 19 at a position opposite the offset portion 19a—see Figure 1. After the parts are thus positioned the working tool T is adjusted longitudinally by means of sleeve 40 and lock nut 41, so that the projecting bead portion of the tool is directly opposite the groove g of the die. The sleeve 40 has a head C which contacts the inner face of the beading tool shoulder t. The end of the tube or work W is then positioned against the outer face of the beading tool shoulder t and clamped. In this last mentioned manner the end of the tube is properly located with respect to the die. The stop screw 30 is then adjusted to limit the extent of beading movement, and locked by the nut 31. This adjustment prevents the operator from over-beading or overflaring the tube, so as to excessively thin the tube wall at and adjacent to the beaded portion thereof.

Assuming that it is desired to form a bead or flare in a tubular member W, as illustrated in Figure 1, the extent of the beading or flaring is controlled by the distance between the adjacent portions of the stop member 30 and the tool block 17. The motor M is then started, and the operator starts to move the lever L to the extreme right, as viewed in Figure 1. This last mentioned movement of the lever produces a relative movement of the cam blocks with respect to the tool block, because the offset portion 19a of the slot 19 provides clearance for radial movement of the tool block 17, thereby causing the cam surfaces 16a and 17a to react in such manner as to push the block 17 downwardly off-center, so that the offset portion 19a moves over said pin. When the stop 30 engages the block 17, no further axial movement of the tool-carrier block can occur, because relative movements of the blocks 16 and 17 are prevented. The motor causes the tool-carrier to rotate with the spindle and cam blocks, and the tool is rotatably mounted in the tool-carrier block, so that as the tool shifts off-center, the bead in the tube is progressively formed by a rolling action of the tool within the tubular member W. This rolling action produces a bead superior to that made if the tool were rigidly mounted in the tool-carrier-block and formed the bead by a sliding frictional action. The extent of beading, as above stated, is limited by the engagement of the end of the stop 30 with the tool block 17.

At the completion of the beading operation, the lever L is rocked to the left to the extreme dotted line position, as viewed in Figure 1, so as to recenter the tool and withdraw the same from within the work W, permitting removal of the completed beaded tube. After removal of the latter, the lever L is again rocked to the solid line position to condition the machine for positioning and clamping the next tube and the described operation repeated. If it is desired to flare the end of the tube, the tube-end is properly located with respect to the die by engaging said tube end with a conical surfaced tool T', as shown in Figure 6, while the lever L is in solid line position. Thereafter, the operations are identical with those previously described.

Referring more particularly to Figures 7 to 10, both inclusive, the spindle 11 is shown as constructed of two halves 11a and 11b, these halves being secured together by means of bolts 11c. Instead of forming the L-slot 19 in the tool-carrier block 17, as previously described, the lower half 11b of the spindle 11 is provided with oppositely disposed recesses a. A block b is located in each of the recesses a, being held in position by screws c, so as to form diametrically opposite L-shape slots d. The complementary pin 20a is mounted in the tool-carrier block 17, with its end portions projected into the said slots d. The operation of these parts, however, is the same as that described in connection with the previously discussed figures of the drawings.

The advantages of the invention will be readily understood by those skilled in the art to which it belongs. For instance, it will be observed that off-center adjustment of the tool-carrier-block may be quickly and accurately effected. Another advantage is that the angular cross-section of the spindle bore, and the complementary cross sections of the cam and the tool-carrier-block effectively insures rotation of said cam and the block with the spindle, while also maintaining them in alignment during relative sliding ad-

justments thereof. An important advantage is that an exceedingly simple complementary cam arrangement is provided by which the extent of off-center movement of the tool-carrier-block may be readily effected.

Having thus explained the nature of the invention and described an operative manner of constructing and using the same, although without attempting to set forth all of the forms in which it may be made, or all of the forms of its use, what is claimed is:

1. In a beading and flaring machine of the character described, a spindle member having an axial bore, means for rotatively supporting the same, cam means axially slidable in said bore and rotatable with the spindle member, a tool-carrier block axially disposed within said cam means and rotatable therewith, said tool carrier block being axially slidable and capable of off-center movements within said cam means, means for imparting limited axial sliding movements to said cam means with respect to said tool-carrier block, and means operated by said relative sliding movements for moving the tool-carrier block to and from an off-center position.

2. In a beading and flaring machine of the character described, a spindle member having an axial bore, means for rotatively supporting the same, cam means axially slidable within said bore and rotatable with the spindle member, a tool-carrier block axially disposed within said cam means and rotatable therewith, said tool carrier block being axially slidable and capable of off-center movements within said cam means, means for imparting sliding movements to the cam means and tool-carrier block together, means for interrupting said movement of the tool-carrier block during continued movement of the cam means, and means operated by the relative sliding movement of the cam means and carrier block for moving the latter to and from an off-center position.

3. In a beading and flaring machine of the character described, a spindle member having an axial bore, means for rotatively supporting the same, cam blocks slidably mounted within said bore and rotatable with the spindle member, a tool-carrier block axially disposed between said cam blocks and rotatable therewith, said tool carrier block being axially slidable and capable of off-center movements between said cam blocks means for imparting limited sliding movements of the cam blocks with respect to said tool-carrier block, and means operated by said relative sliding movements for moving the tool-carrier block to and from an off-center position.

4. In a beading and flaring machine of the character described, a spindle member having an axial bore, means for rotatively supporting the same, cam blocks slidably mounted within said bore and rotatable with the spindle member, a tool-carrier block axially disposed between said cam blocks and rotatable therewith, said tool carrier block being axially slidable and capable of off-center movements between said cam blocks, means for imparting limited sliding movements of the cam blocks with respect to said tool-carrier block, said cam blocks and said tool-carrier block having interengaged complementary cam surfaces for moving the tool-carrier block to and from an off-center position during said relative movement of the cam blocks.

5. In a beading and flaring machine of the character described, a spindle member having an axial bore, means for rotatively supporting the

same, cam means axially slidable in said bore and rotatable with the spindle member, a tool-carrier block axially disposed within said cam means and rotatable therewith, said tool carrier block being axially slidable and capable of off-center movement within said cam means, means for imparting sliding movements to said cam means with respect to said tool-carrier block, means operated by said relative sliding movements for moving the tool-carrier block to and from an off-center position, and means operable by movement of said cam means for limiting the extent of said off-center movement.

6. In a beading and flaring machine of the character described, a spindle member having an axial bore, means for rotatively supporting said spindle, cam blocks slidably mounted within said bore and rotatable with the spindle member, a tool-carrier block axially disposed between said cam blocks and rotatable therewith, said tool carrier block being axially slidable and capable of off-center movements between said cam blocks means for imparting sliding movement of the cam blocks with respect to said tool-carrier block, said cam blocks and said tool-carrier block having interengaged complementary cam surfaces for moving the tool-carrier block to and from an off-center position during said relative movement of the cam blocks, and means operated by sliding movement of said cam blocks for limiting the extent of said off-center movement.

7. In a beading and flaring machine of the character described, a spindle member having an axial bore of angular cross section, means for rotatively supporting said spindle, cam members slidably mounted in said bore and having a cross section complementary to the cross section of said bore, a tool-carrier block axially disposed between said cam members and rotatable therewith, said tool carrier member having a cross section complementary to the cross section of the cam members and being axially slidable and capable of off-center movements between said cam members, means for imparting sliding movement to the cam members relative to said tool-carrier block, and means operated by said relative sliding movements for moving the tool-carrier block to and from an off-center position.

8. In a beading and flaring machine of the character described, a spindle member having an axial bore of angular cross section, means for rotatively supporting said spindle, cam members slidably mounted in said bore and having a cross section complementary to the cross section thereof, a tool-carrier block axially disposed between said cam members and rotatable therewith, said tool carrier block having a cross section complementary to the cross section of the cam members and being axially slidable and capable of off-center movements between said cam members, means for imparting sliding movement to the cam members with respect to the tool-carrier block, means operated by relative sliding movements for moving the tool-carrier block to and from an off-center position, and an adjustable stop movable with said cam members for limiting the extent of said off-center movement.

9. In a beading and flaring machine of the character described, a spindle member having an axial bore of rectangular cross section, means for rotatively supporting said spindle, axially slidable cam blocks located within said bore and having a cross section complementary to the latter, a tool carrier block axially disposed between and rotatable with said cam blocks, said tool

carrier member having a cross section complementary to the cross section of the cam blocks and being axially slidable and capable of off-center movements between said cam blocks, means for imparting sliding axial movements to said cam blocks and also to said tool-carrier block, and means for interrupting the sliding movement of said tool-carrier block during continued movement of the cam blocks, said cam blocks and said tool-carrier block having complementary cam surfaces for moving said tool-carrier block to and from off-center positions during said relative movement.

10. In a beading and flaring machine of the character described, a spindle member having an axial bore of rectangular cross section, means for rotatively supporting said spindle member, cam members slidably mounted within said bore and also of angular cross section, a tool-carrier block axially disposed between the cam members and rotatable therewith, said tool carrier block being of angular cross section and axially slidable and capable of off-center movements between said cam members, means for imparting simultaneous sliding movements to the cam members and the tool-carrier block, and means for interrupting movement of the tool-carrier block during continued movement of the cam members, said tool-carrier block and said cam members having interengaging surfaces so positioned as to move the tool-carrier block off-center during relative movement of the cam members with respect to the tool-carrier block.

11. In a beading and flaring machine of the character described, a spindle member having an axial bore, means for rotatively supporting said spindle member, an axially slidable tool-carrier block slidably located within said bore, axially slidable cam members also located within the bore and slidable with respect to said tool-carrier block, said cam members and said tool-carrier block having complementary cam surfaces for imparting off-center movement to the tool-carrier block during the relative sliding movement of the cam members, means for imparting axial sliding movements to said cam members, means for temporarily connecting the cam members and the tool-carrier block so that they will travel together during such movement of the cam members, and means for arresting said travel of the tool-carrier block after a predetermined distance of such travel, said tool-carrier block being then free for off-center movement.

12. In a beading and flaring machine of the character described, a spindle member having an axial bore, means for rotatively supporting said spindle member, an axially slidable tool-carrier block located within said bore and having a longitudinal slot therein provided with an offset portion at one end, axially slidable cam members located within said bore and slidable with respect to the tool-carrier block, said cam members and said tool-carrier block having complementary cam surfaces for imparting off-center movement to the tool-carrier block during sliding movement of the cam members with respect thereto, and a pin carried by said spindle member and extended through said slot, so as to arrest sliding movement of the tool-carrier block after a limited distance of such travel, said tool-carrier block being free for off-center movement while said pin is in register with the offset portion of said slot.

13. In a beading and flaring machine of the character described, a spindle member having an

axial bore, means for rotatively supporting said spindle member, an axially slidable tool-carrier block located within said bore and having a longitudinal slot therein provided with an offset portion at one end, axially slidable cam members located within said bore and slidable with respect to the tool-carrier block, said cam members and said tool-carrier block having complementary cam surfaces for imparting off-center movement to the tool-carrier block during sliding movement of the cam members with respect thereto, a pin carried by said spindle member and extended through said slot, so as to arrest sliding movement of the tool-carrier block after a limited distance of such travel, said tool-carrier block being free for off-center movement while said pin is in register with the offset portion of said slot, and means for limiting extent of said off-center movement.

20. 14. In a beading and flaring machine of the character described, a spindle member having an axial bore, means for rotatively supporting said spindle member, an axially slidable tool-carrier block located within said bore and having a longitudinal slot therein provided with an offset portion at one end, axially slidable cam members located within said bore and slidable with respect to the tool-carrier block, said cam members and said tool-carrier block having complementary cam surfaces for imparting off-center movement to the tool-carrier block during sliding movement of the cam members with respect thereto, a pin carried by said spindle member and extended through said slot, so as to arrest sliding movement of the tool-carrier block after a limited distance of such travel, said tool-carrier block being free for off-center movement while said pin is in register with the offset portion of said slot, and means for limiting extent of said off-center movement.

25. 15. In a beading and flaring machine of the character described, a spindle member having an axial bore, means for rotatively supporting said spindle member, an axially slidable tool-carrier block located within said bore and having a longitudinal slot therein provided with an offset portion at one end, an operating block slidably mounted within said bore, cam blocks connected with said operating block, said cam blocks and operating block being relatively slidable with respect to said tool-carrier block, said cam blocks and said tool-carrier block having complementary cam surfaces for imparting off-center movement to the tool-carrier block during said relative sliding movement, a pin carried by said spindle member and extended through said slot, so as to arrest sliding movement of the tool-carrier block after a limited distance of such travel, said tool-carrier block being free for off-center movement while said pin is in register with the offset portion of said slot, and a stop member adjustably mounted within said operating block and positioned to engage the inner end of the tool-carrier block, so as to limit the extent of said off-center movement.

30. 16. In a beading and flaring machine of the character described, a spindle member having an axial bore, said spindle having longitudinal slots therein each provided with an offset at one end, an axially slidable tool-carrier block located within said bore, axially slidable cam-members also located within said bore and slidable with respect to the tool-carrier block, said cam members and said tool-carrier block having complementary cam-surfaces for imparting off-center movements to the tool-carrier block during sliding movement of

the cam members with respect thereto, and a pin mounted in the tool-carrier block and extended through said recesses, so as to arrest sliding movement of the tool-carrier block after a limited distance of such travel, said tool-carrier block being free for off-center movement while said pin is in register with the offset portion of said slot.

17. In a beading and flaring machine of the character described, a spindle member formed of complementary sections and having an axial bore, one of said sections having oppositely disposed openings therein, blocks secured within said openings to form longitudinal slots each provided with an offset at one end, an axially slidable tool-carrier block located within said bore, axially slidable cam-members also located within said bore and slidable with respect to the tool-carrier block, said cam members and said tool-carrier block having complementary cam-surfaces for imparting off-center movements to the tool-carrier block during sliding movement of the cam members with respect thereto, and a pin mounted in the tool-carrier block and extended through said recesses, so as to arrest sliding movement of the tool-carrier block after a limited distance of such travel, said tool-carrier block being free for off-center movement while said pin is in register with the offset portion of said slot.

18. In a beading and flaring machine of the character described, a spindle member formed of two complementary sections of semicircular cross-section, the lower member being provided with oppositely disposed recesses, blocks removably secured within said recesses, and cooperating with the latter to provide longitudinal slots each having an offset at one end, means for securing said sections together, so as to provide a longitudinal bore, an axially slidable tool-carrier block located within said bore, axially slidable cam-members

also located within said bore and slidable with respect to the tool-carrier block, said cam members and said tool-carrier block having complementary cam-surfaces for imparting off-center movements to the tool-carrier block during sliding movement of the cam members with respect thereto, and a pin mounted in the tool-carrier block and extended through said recesses, so as to arrest sliding movement of the tool-carrier block after a limited distance of such travel, said tool-carrier block being free for off-center movement while said pin is in register with the offset portion of said slot.
